UNITED STATES PATENT OFFICE

PRESTON C. WEST, OF CHICAGO, ILLINOIS, ASSIGNOR TO P. C. WEST MFG. CO. INC., OF CHICAGO, ILLINOIS, A CORPORATION OF ILLINOIS

CAN OPENER

Application filed November 16, 1925. Serial No. 69,213.

My invention relates to can openers and particularly to that type adapted to be applied to the bead of a can and adapted while being held manually in position to cut the top 5 out of the can inside the bead. It is one of the objects of my invention to provide in a construction of this type means for cutting the top at its extreme outer edge just inside 10 of the bead, and for smoothing the cut edge down into tight contact with the wall of the can below the bead.

It is another object of my invention to provide a device of this kind comprising a tongs device upon which the cutter and its cooperating part are mounted, being so arranged that 15 the cutter is moved out of operative position when the handle members are pressed together. It is still another object of my invention to provide spring means for holding 20 the cutter in operative position, so arranged that under normal conditions the cutter is pressed with the desired force against the tin being cut regardless of what the thickness of the tin or the thickness of the bead may 25 be, and that when the cutter comes into contact with the seam at the side of the can the cutter yields readily in order to pass.

It is another object of my invention to improve the driving means for devices of this 30 type whereby the roller which engages the outer face of the bead of the can is rotated positively from the driving means for the cutter and the roller engaging the inside face of the bead for moving the tin into operative 35 relation to the cutter by the rotation of the can as a whole, and whereby all of such parts are driven preferably by a suitable motor which is mounted in position so as to be substantially balanced on the opposite side of 40 the handle from that at which the cutter and its cooperating parts are located.

It is another object of my invention to provide improved gripping means adapted by engagement with the bead of a can to hold the 45 cutter in proper angular position for operation, and to provide a support for the device adapted by contact with the bead at a point spaced a short distance from the cutter and the gripping means to maintain the operative 50 position of the device.

It is another object of my invention to improve the cutter and the cooperating parts which hold the tin in position for cutting, the arrangement being such that the tin is first pressed into the shape of a groove at the 55 bottom of which pressure is then applied by the cutter for tearing the tin rather than for cutting it by a shearing operation.

A further object of my invention is the provision of a device so constructed that in its 60 operation of cutting out a can top it will flare outwardly the upper end of the can walls thereby facilitating ready removal of the contents of the can in whole pieces, this result being particularly desirable with such 65 tender food products as asparagus tips, sardines, etc.

Another object of my invention is the provision of a device so constructed that it will serve both for handling a can and for cutting out the top of the can. To this end, 70 I provide suitable handle means in combination with the other parts, all so arranged that a can may be held and manipulated before, during and after the cutting operation, thus making it possible to pick up a can, the contents of which have been heated or chilled, cut out the top and then serve the food directly from the can.

It is another object of my invention to improve devices of this type in sundry details hereinafter pointed out. The preferred means by which I have accomplished my several objects is illustrated in the accompanying drawings and is hereinafter specifically described. That which I believe to be new and desire to cover by this application is set forth in the claims.

In the drawings—

Fig. 1 is a face view of my improved device, 90 partly broken away, and with a portion of the housing for the driving mechanism removed;

Fig. 2 is a top plan view of the parts shown in Fig. 1, but with the entire housing 95 for the driving mechanism removed;

Fig. 3 is an enlarged detail view, being substantially a vertical cross-section taken at line 3—3 of Fig. 1;

Fig. 4 is a fragmentary view on an enlarged 100

scale, showing the cutter and the cooperating roller in operative position on the bead of a can which is shown in vertical cross-section; and

3 Fig. 5 is a view similar to Fig. 1 but showing a modified form of construction.

Referring now particularly to Figs. 1 to 4, in which corresponding parts are indicated by the same reference characters,—10 and 11 indicate the bars of a tongs device which are pivotally connected together by means of a pin 12, the bars 10 and 11 being arranged in parallel relation rather than in crossed relation, so that when the handle portion 13 of the bar 10 is pressed toward the bar 11 the opposite ends of the bars are moved away from each other. In the construction shown, the bars 10 and 11 are made of sheet metal bent into channel form, in the handle portion 13 of the bar 10 the channel being extended at its edges into tubular form.

In the short end of the arm 10, I have mounted a bushing 14 which is held in position by a pin 15, the bushing 14 serving as a spacing block between the flange portions of the end of the handle, as is best shown in Fig. 2. Upon the outer end of the pin or shaft 15, I have mounted a housing comprising members 16 and 17 held together by a plurality of bolts 18, the member 16 being revolvably mounted with respect to the shaft 15 so that the housing is supported by said shaft. Upon the end of the shaft 15 within the housing, I have provided a worm gear 19 keyed in position. At the upper edge of the housing I have mounted a worm 20 meshing with the worm gear 19, such worm being mounted upon the end of a shaft 21. The shaft 21 extends through an opening 22 in the wall of the handle member 10 so as to pass through the tubular handle portion 13, being connected at its end portion with the drive shaft of an electric motor 23 which is mounted by means of arms 24 upon the said handle portion 13. The arrangement is such that when the motor 23 operates power is transmitted from the motor to the shaft 15 for driving it.

In the short end of the bar 11, I have mounted a pin or shaft 25 which holds in position a sleeve or bushing 26 acting as a spacing block. The shaft 25 is operatively connected with the shaft 15 by means of gears 27 and 28 keyed upon the shafts respectively, the gear 28 being mounted between the bar 10 and the housing member 16, as is best shown in Fig. 3.

As is best shown in Fig. 3, the shaft 15 is provided at one end with a roller 29 rigidly mounted thereon, and a rotary cutter 30 is mounted upon such roller, being held in position through the medium of the pin or shaft 15 which is provided upon its outer end with a head 31 for holding the cutter in position. Upon the pin or shaft 25 in position opposite

the roller 29 I have provided a roller 32 which is formed integrally with the shaft 25 or is otherwise secured thereto by any suitable means.

About the pin 12 which connects the bars 10 and 11 of my tongs device, I have mounted a strong spring 33, the end portions of which bear against the web portions of the bars 10 and 11, as is best shown in Fig. 1, serving to hold the handle portion 13 yieldingly at the limit of its movement away from the bar 11.

When the can opener is to be applied to a can, such as the can 34 illustrated fragmentarily in Fig. 4, such can comprising a bead portion 35 extending upwardly a short distance beyond the plate portion 36 constituting the "top" of the can,—the operator grasps the handle 13 of the bar 10, together with the oppositely disposed portion of the bar 11. Upon pressing the bars toward each other against the action of the spring 33, the roller 29 and cutter 30 are moved away from the roller 32 so as to permit the device to be applied to the can with the roller 29 in contact with the inner face of the bead 35 near its top portion and with the roller 32 in engagement with the outer face of the bead near its lower edge, the rollers 29 and 32 serving by such engagement to hold the cutter 30 in oblique position with respect to the can, all as best shown in Fig. 4. When power is applied to the shafts 15 and 25 for rotating the cutter 30 and the rollers, the rollers bear frictionally upon the bead 35 for causing the can to be moved with respect to the cutter, serving to bring the cutter into contact with the top of the can about its extreme outer edge in close proximity to the inner face of the bead. At the beginning of the rotary movement of the cutter and the movement of the can with respect to the cutter, the cutter 30 penetrates the tin, as indicated in Fig. 4, if such penetration has not taken place upon the application of the device and before the rotation is started. As the can is rotated with respect to the operating parts, the cutter 30 serves to cut the top out of the can so as to be ready for easy removal.

As is clearly shown in Fig. 4, the roller 29 engages the inner face of the bead in approximately the lowest permissible position of the roller unless the roller is permitted to move toward the right in said Fig. 4. The roller 32 engages the bottom portion of the bead at its outer face in approximately the highest position permissible, unless the roller is to be permitted to move toward the left in said Fig. 4. As a result of this construction, the tongs device is adapted to grip the bead and to hold the can very firmly in position. For assisting in holding the device in position I have provided an arm 37 extending in oblique position with respect to the axes about which the cutter and the rollers revolve, which

arm engages the top edge of the bead 35 at a short distance from the cutter 30, such arm 37 being preferably formed integrally with the bar 10. In the normal position of the 5 device upon the can, the arm 37 bears flatly against the top edge of the bead.

As is clearly shown in Fig. 3, the roller 32 is provided with a groove 38 at the point opposite the cutter 30, such groove being adapted 10 to relieve the edge of the cutter 30 when the device is not in position upon a can, the contact of the bars 10 and 11 with each other as indicated in Fig. 3 being adapted to limit the movement of the cutter 30 toward the roller 32.

When the device is in position upon a can, the end of the roller 32, by contact with the outer face of the wall of the can, acts as a stop with respect to any possible twisting 20 tendency of the device about a horizontal axis, as is clearly shown in Fig. 4.

In operation, the edge of the cutter 30 extends through the cut or tear of the tin at the point where the top 36 is severed from 25 the head, the extreme edge of the cutter being adapted normally to come in contact with the inner face of the wall of the can so as to bulge the metal outwardly to a slight extent and so as to score the face of the wall 30 very lightly as indicated by the line 39 in said Fig. 4. The proportions of the parts are such, however, that the cutter is prevented from severing the metal at this point.

In the ordinary use of my device, the cutter 30 cuts the top substantially at the inner face of the bead, but at such a distance therefrom that there is a very narrow strip of the top 36 which is not severed from the can. This narrow strip which before the cutting 35 operation stands in transverse position is pressed down into vertically extending position in close, smooth and even contact with the inner face of the wall of the can, with the result that the inner face of the can when the top 36 is removed is perfectly smooth and without projecting edges which might be likely to cut the hands of the operator, to interfere with the easy removal of the contents 45 of the can, or to tear or disfigure the contents 50 when being removed.

No support of any kind is provided by my improved device for the bottom face of the tin at the point where the cutter is operating, so that a shearing cut is not possible. On the contrary, the metal of the top 36 is first 55 pressed down into the form of a groove slightly in advance of the cutter and the pressure of the cutter at the bottom of the groove 60 serves to tear the tin rather than to cut it. The line at which the tin is severed is however so close to the bead 35 that the tin has the required support. As is clearly shown in Fig. 4, the upper end of the can is flared outwardly by the cutting operation, with the 65

result that the cut-out portion of the top 36 is capable of ready removal from the can.

When the device is in position on a can, the cutter 30 and the rollers 29 and 32 are held in operative position solely by the force 70 of the spring 33, the action of which is entirely automatic so as to leave nothing to either the skill or the judgment of the operator. The result is that either the roller 29 or the roller 32 is adapted to yield readily for permitting the device to pass the vertically disposed seam at one side of the can. Also by reason of this spring tensioning of the gripping means, the device is adapted to operate to advantage upon different thicknesses of 75 tin and upon cans in which the size of a bead 35 varies to a considerable extent in either depth or thickness.

By the use of the positive drive of the shaft 25 and the roller 32 from the shaft 15 through the medium of the gears 27 and 28, I have provided positively-operating means for turning the can with respect to the cutter whereby the operation of the device is made much more sure and satisfactory. At the 80 same time, the device as a whole is kept fairly light and capable of being handled easily. In the preferred operation of the device, after the rollers are applied into gripping position upon the bead, the operator releases the 85 bar 11 and steadies the device and the can by the use of the handle 13 by itself, so that no pressure shall be applied upon the bar 11 against the action of the spring 33. The position of the motor 23 at the end of the arm 90 or bar 10 at the opposite side of the handle 13 from that at which the operating devices are located insures that the parts shall be substantially balanced so that the device is very 95 easily held in position for operation.

By providing rollers of the formation shown in Fig. 4, engaging the bead on the inside at its upper edge and on the outside at its lower edge, and each provided with a curved surface portion serving in effect as 100 a shoulder for limiting the vertical movement of the roller with respect to the bead, and by positioning the cutter 30 so that its contact with the top 36 comes below the point of contact of the roller 32 on the outer face of the 105 body, I have provided for a very secure gripping of the can by the device. The grip of the device on the can is such that it may safely be used as a handle for lifting the can 110 after the top is removed, making the device 115 thus particularly useful for opening and emptying cans which are heated prior to the opening operation.

As is clearly shown in Fig. 4, the face of the cutter 30 adjacent to the roller 29 is beveled slightly at its outer edge, while the other face is beveled considerably more. The beveling of the cutter is important with respect to the proper cooperation of the cutter with the remaining parts, the beveling of the face 120

adjacent to the bead 35 being particularly important for preventing the cutter from cutting through the bead or climbing up the face of the bead at a point of curvature. I have found in practice that by the use of the means as shown in Fig. 4 the device is enabled to operate very satisfactorily on any of the ordinary types of can on the market in which an upstanding bead is provided, and including the sardine can type. By reason of the fact that the obliquely positioned cutter extends under the edge of the bead where it is cut and into close proximity to a portion of the roller 32 but on the opposite face of the side wall of the can, the device is held very firmly in position on the bead.

Referring now to Fig. 5, in which a modified form of construction is shown, corresponding parts are indicated by the same reference characters. In this construction the shaft 15 has mounted thereon a crank handle 40 by which the cutter 30 and the gripping rollers 29 and 32 are driven in lieu of the motor 23 and the transmission mechanism connecting the motor with said shaft. With the device held in position by the left hand of the operator grasping the handle 13, the operator can very easily turn the shaft 15 by the use of the crank 40, a few turns of the crank being sufficient for cutting the top from a can.

While I prefer to employ the construction as illustrated in my drawings and as above described, it will be understood that I do not wish to limit myself to the precise form shown except as the same may be hereinafter specifically claimed, inasmuch as it is evident that changes may well be made in the construction and arrangement without departing from the spirit of my invention.

I claim:

1. A can opener, comprising a cutter, a tongs device on one bar of which said cutter is revolvably mounted, means for rotating the cutter, means carried by the respective bars of the tongs device for gripping a can for holding the cutter in operative position, and a spring for holding said gripping means in operative relation.

2. A can opener, comprising a cutter, a tongs device on one bar of which said cutter is revolvably mounted, means for rotating the cutter, means carried by the respective bars of the tongs device for gripping a can for holding the cutter in operative position and adapted to be loosened on the can when the bars of the tongs device are pressed toward each other, and a spring for holding said bars yieldingly at the limit of their movement away from each other.

3. A can opener, comprising a cutter, a tongs device on one bar of which said cutter is revolvably mounted, means for rotating the cutter, and positively driven rollers carried by the respective bars of the tongs device

adapted by engagement with opposite faces of a part of a can to hold the can in operative position and to give the cutter and the can a relative movement for causing the cutter to cut the top out of the can, the bars of said tongs device being so arranged that when the bars are pressed toward each other the said rollers are loosened with respect to the can.

4. A can opener, comprising a cutter, a tongs device on one bar of which said cutter is revolvably mounted, means for rotating the cutter, means carried by the respective bars of the tongs device for gripping a can for holding the cutter in operative position, and a spring for holding said gripping means in operative relation, the bars of said tongs device being so arranged that when the bars are pressed toward each other against the action of said spring the device is loosened with respect to the can.

5. A can opener, comprising a cutter, a tongs device on one bar of which said cutter is revolvably mounted, means for rotating the cutter, positively driven rollers carried by the respective bars of the tongs device adapted by engagement with opposite faces of a part of the can to hold the cutter in operative position and to give the cutter and the can a relative movement for causing the cutter to cut the top out of the can, and a spring for holding the bars of the tongs device in position for maintaining the rollers in gripping engagement with the can, the said bars of the tongs device being so arranged that when the bars are pressed toward each other against the action of the spring the rollers are loosened with respect to the can.

6. A can opener, comprising a cutter, a tongs device on one bar of which said cutter is revolvably mounted, means for rotating the cutter, means carried by the respective bars of the tongs device for gripping a can for holding the cutter in operative engagement with the top of the can inside of the bead, a spring for holding the bars of the tongs device yieldingly in position for maintaining the grip on the can, and means for giving the cutter and the can a relative movement for causing the cutter to cut the top out of the can.

7. A can opener, comprising a cutter, a tongs device on one bar of which said cutter is revolvably mounted, means for rotating the cutter, positively driven rollers carried by the respective bars of the tongs device adapted by engagement with opposite faces of a part of the can to hold the cutter in operative position engaging the top of the can and adapted by their rotation to give the cutter and the can a relative movement for causing the cutter to cut the top from the can, and a spring for holding the bars of the tongs de-

vice yieldingly in position for maintaining the grip on the can.

8. A can opener, comprising a cutter, a tongs device on one bar of which said cutter is revolubly mounted, means for rotating the cutter, positively driven rollers carried by the respective bars of the tongs device adapted by engagement with opposite faces of a part of the can to hold the cutter in operative position engaging the top of the can inside of the bead and adapted by their rotation to give the cutter and the can a relative movement for causing the cutter to cut the top out of the can, and a spring for holding the bars of the tongs device yieldingly in position for maintaining the grip of the rollers on the can.

9. A can opener, comprising a cutter, a supporting member on which said cutter is revolubly mounted, a handle by which said supporting member may be held manually with the cutter in oblique position above the can operatively engaging the top of the can inside of the bead, means for rotating the cutter, positively driven roller means engaging opposite faces of a part of the can for giving the can and the cutter a relative movement for causing the cutter to cut the top out of the can and also serving by their engagement with the can to assist in holding the cutter in operative position, and a spring for holding the rollers yieldingly in operative engagement with the can but adapted to yield to accommodate irregularities in the proportions of the engaged part of the can.

10. A can opener, comprising a cutter, a tongs device on one bar of which said cutter is revolubly mounted, means for rotating the cutter, rollers carried by the respective bars of the tongs device adapted by engagement with opposite faces of the bead of a can to hold the cutter in oblique position engaging the top of the can inside of the bead, means for giving the cutter and the can a relative movement for causing the cutter to cut the top out of the can, and a spring for holding the bars of the tongs device yieldingly in position for maintaining the grip of the rollers on the can.

11. A can opener, comprising a cutter, a tongs device on one bar of which said cutter is revolubly mounted, means for rotating the cutter, rollers carried by the respective bars of the tongs device adapted to be separated by the action of the tongs device for receiving between them the bead of a can and adapted by engagement with the opposite faces of said bead to hold the cutter in oblique position engaging the top of the can inside of the bead in close proximity to the inner face thereof, means for pressing the rollers against said bead, and means for positively driving said rollers in unison with said cutter for giving the can and the cutter

a relative movement for causing the cutter to cut the top out of the can.

12. A can opener, comprising a cutter, a tongs device on one bar of which said cutter is revolubly mounted, means for rotating the cutter, rollers carried by the respective bars of the tongs device adapted by engagement with the opposite faces of the bead of the can to hold the cutter in oblique position engaging the top of the can inside of the bead in close proximity to the inner face thereof, means for positively driving said rollers in unison with said cutter for giving the can and the cutter a relative movement for causing the cutter to cut the top out of the can, and a spring for holding the bars of the tongs device yieldingly in position for maintaining the grip of the rollers upon the bead.

13. A can opener, comprising a cutter, a supporting member on which said cutter is revolubly mounted, a handle by which said supporting member may be held manually with the cutter in operative position with respect to a can, a motor, means driven by the motor for rotating the cutter, and other means driven by the motor adapted in co-operation with said cutter to give the can and the cutter a relative movement for causing the cutter to cut the top from the can.

14. A can opener, comprising a cutter, a bar on which said cutter is revolubly mounted, a handle by which said bar may be held manually with the cutter in operative position with respect to a can, a motor mounted on said bar on the opposite side of the handle from that at which said cutter is located and so arranged that the parts are substantially balanced on opposite sides of the handle, means driven by the motor for rotating the cutter, and other means driven by the motor and cooperating with the cutter for giving the can and the cutter a relative movement for causing the cutter to cut the top from the can.

15. A can opener, comprising a shaft, a cutter mounted on said shaft, a supporting member on which said shaft is journaled, a handle by which said supporting member may be held manually with the cutter in operative position with respect to a can, a motor mounted on said supporting member, a worm gear mounted on said shaft, a worm mounted on the motor shaft in position to mesh with said worm gear, and means driven by said first named shaft for giving the can and the cutter a relative movement for causing the cutter to cut the top from the can.

16. A can opener, comprising a shaft, a cutter mounted on said shaft, a bar on which said shaft is journaled, a handle by which said bar may be held manually with the cutter in operative position with respect to a can, a motor mounted on said bar, a worm gear mounted on said shaft, a housing mounted on said shaft and surrounding said worm

gear, a worm mounted within said housing on the motor shaft in position to mesh with said worm gear, and means driven by said first named shaft for giving the can and the cutter a relative movement for causing the cutter to cut the top from the can, said worm by its engagement with the housing being adapted to hold the housing in fixed position.

17. A can opener, comprising a cutter, a tong device on one bar of which said cutter is revolvably mounted, rollers carried by the bars of said tong device adapted by engagement with the opposite faces of the bead of a can to hold the cutter in close proximity to the inner face of said bead, a spring for holding said bars yieldingly in position for maintaining the rollers in gripping engagement with the bead, and means for rotating said cutter and said rollers for giving the cutter and the can a relative movement, serving to cause the cutter to cut the top out of the can and to smooth down against the inside wall of the can any remaining portion of the top which before the cutting operation stood normally in transversely extending position.

18. A can opener, comprising a cutter, rollers adapted by engagement with opposite faces of the bead of the can to hold the cutter in oblique position above the can in close proximity to the inner face of the bead, means for rotating the cutter, means for rotating said rollers for giving the can and the cutter a relative movement for causing the cutter to cut the top out of the can and to smooth down against the inside wall of the can any remaining portion of the top which before the cutting operation stood normally in transversely extending position, and a spring for holding said rollers yieldingly in gripping engagement with said bead.

19. A can opener, comprising a roller adapted to engage the inner face of the bead of a can near its upper edge and extending over said bead, a second roller adapted to engage the outer face of the bead near its lower edge and extending under the bead, means for holding said rollers in operative position to grip said bead, a cutter held by said rollers in operative position with respect to the can for cutting the top from the can along a line adjacent to the inner face of the bead, and means for rotating the cutter and the rollers for giving the cutter and the can a relative movement for causing the cutter to cut the top from the can.

20. A can opener, comprising a roller adapted to engage the inner face of the bead of a can near its upper edge and having a portion overlying the bead adapted to limit the downward movement of the roller, a second roller adapted to engage the outer face of the bead near its lower edge and having a portion extending under the bead adapted to limit the upward movement of said second roller, means for holding the

rollers in gripping position on the bead so as to prevent angular movement of the bead with respect to the rollers, means for rotating the rollers for moving the can with respect thereto, and means adapted upon such relative movement to cut the top from the can.

21. A can opener, comprising rollers adapted to engage opposite faces of the bead of a can, a cutter in position to engage the top of the can adjacent to said rollers, a spring for pressing said rollers toward each other for gripping the bead and serving thus to hold the axes of the rollers in oblique position with respect to the can, and means for rotating the rollers serving to give the can and the cutter a relative movement for cutting the top from the can.

22. A can opener, comprising a cutter, means adapted by engagement with oppositely disposed faces of the bead of a can to hold said cutter in operative engagement with the top of the can inside of the bead, and means for giving the cutter and the can a relative movement for causing the cutter to cut the top out of the can, the cutter being provided with a wide beveled edge portion at the face thereof removed from the bead and with a comparatively narrow beveled edge portion at the face adjacent to the bead.

23. A can opener, comprising in combination a cutter, a supporting element on which said cutter is revolvably mounted, a second supporting element movably mounted with respect to said first named supporting element, a roller revolvably mounted on said second supporting element adapted to engage the outer face of the bead of a can near its lower edge and to engage the outer face of the wall of the can below the bead in close proximity thereto, a second roller revolvably mounted on said first named supporting element adjacent to said cutter adapted to engage the inner face of the bead near its upper edge and adapted thereby to hold the supporting elements and the cutter firmly in position angularly with respect to the bead, means for rotating the rollers for giving the can and the cutter a relative movement for causing the cutter to cut the top out of the can, and a spring for holding the supporting elements effectively in position to maintain the grip of the rollers on the can.

24. A can opener, comprising in combination a cutter, a supporting element on which said cutter is revolvably mounted, a second supporting element movably mounted with respect to said first named supporting element, rollers carried by said supporting elements respectively adapted by engagement with opposite faces of the bead of a can to hold the cutter firmly in oblique position engaging the top of the can inside of the bead, the lower roller being positioned to support the outer wall of the can both above and below the cutter in close proximity thereto and hav-

ing a groove thereabout opposite the edge of the cutter, means for rotating the rollers for giving the can and the cutter a relative movement for causing the cutter to cut the top out of the can, and a spring for holding the supporting elements effectively in position to maintain the grip of the rollers on the can.

25. A can opener comprising a handle, an arm articulately connected to said handle, cooperating elements consisting of a disk journaled on said handle and a feeding wheel journaled on said arm and adapted to cooperate with said cutting disk, to frictionally grip the can, a spring of sufficient strength to effect a penetration of the can wall and maintain the cutting disk in operative relation to the wheel during the cutting operation and means to rotate one of said cooperating elements.

26. A can opener, comprising a cutter, a supporting member on which said cutter is revolvably mounted, a second supporting member movably mounted with respect to said first named supporting member, rollers carried by said supporting members adapted by engagement with opposite faces of the bead of a can to hold the cutter in oblique position engaging the top of the can inside of the bead, means for rotating said rollers for giving the can and the cutter a relative movement for causing the cutter to cut the top out of the can, and a spring for holding the supporting members effectively in position to maintain the grip of the rollers on the can.

27. A can opener, comprising in combination a frame member, a motor mounted on said frame member, a supporting member movably mounted on said frame member, a cutter revolvably mounted on one of said members, roller means revolvably mounted on the other of said members adapted by cooperation with said cutter to hold a can in operative position with respect to the cutter, and means actuated by said motor for driving both said roller means and said cutter serving to give the cutter and the can a relative movement for cutting the top from the can.

28. A can opener, comprising in combination a frame member, a motor mounted on said frame member, a supporting member revolvably mounted on said frame member, two shafts revolvably mounted on said members in substantial parallelism with each other, a cutter non-rotatably mounted with respect to one of said shafts, a roller non-rotatably mounted with respect to the other of said shafts, means for moving one of said shafts toward the other for bringing the cutter and the roller into operative gripping engagement with opposite faces of a portion of a can, and means actuated by said motor for driving both of said shafts serving to give the cutter and the can a relative movement for cutting the top from the can.

29. A can opener, comprising in combination a roller adapted to engage the inner face of the bead of a can, a second roller adapted to engage the outer face of the bead and having a portion extending into engagement with the outer face of the can below said bead, a cutter held by said rollers when tightened on said bead in position to engage the top of the can adjacent to said bead on the inner face thereof, means for holding the rollers in tightened gripping position on the bead, and means for rotating the rollers for moving the can with respect to the cutter serving to cut the top from the can, said rollers being so shaped and arranged that upon said cutting operation the upper end portion of the can is flared outwardly.

30. A can opener, comprising in combination a supporting member, a cutter revolvably mounted on said member, a second supporting member movably mounted with respect to said first named supporting member, a roller revolvably mounted on said first named supporting member adapted to engage the inner face of the bead of a can near its upper edge and having a portion overlying the bead adapted to limit the downward movement of the roller, a second roller revolvably mounted on said second supporting member adapted to engage the outer face of the bead adjacent to said first named roller and having a portion extending under the bead adapted to limit the upward movement of the second roller and extending into engagement with the outer face of the can below said cutter tending when the rollers are tightened in position on the bead to bend the wall of the can outwardly at its upper end portion, means for holding the rollers in tightened gripping position on the bead so as to prevent angular movement of the bead with respect to the rollers, and means for rotating said rollers for moving the can with respect to the cutter serving to cut the top from the can and to flare the upper end portion of the can.

31. A device adapted to serve both for handling a can and for cutting the top out of the can, comprising, in combination, a cutter, a supporting member on which said cutter is revolvably mounted, a second supporting member movably mounted with respect to said first named supporting member, rollers carried by said supporting members adapted by engagement with opposite faces of the bead of a can to hold the cutter in oblique position engaging the top of the can inside of the bead, means for rotating said rollers for giving the can and the cutter a relative movement for causing the cutter to cut the top out of the can, a spring for holding the supporting members effectively in position to maintain the grip of the rollers on the can, and handle means operatively connected with said supporting members for holding and ma-

nipulating the can before, during and after the cutting operation.

32. A device adapted to serve both for handling a can and for cutting the top out of the can, comprising, in combination, a cutter, a supporting element on which said cutter is revolvably mounted, a second supporting element movably mounted with respect to said first named supporting element, a roller revolvably mounted on said second supporting element adapted to engage the outer face of the bead of a can near its lower edge and to engage the outer face of the wall of the can below the bead in close proximity thereto, a second roller revolvably mounted on said first named supporting element adjacent to said cutter adapted to engage the inner face of the bead near its upper edge and adapted thereby to hold the supporting elements and the cutter firmly in position angularly with respect to the bead, means for rotating the rollers for giving the can and the cutter a relative movement for causing the cutter to cut the top out of the can, a spring for holding the supporting elements effectively in position to maintain the grip of the rollers on the can, and handle means operatively connected with said supporting elements for holding and manipulating the can before, during and after the cutting operation.
